UNITED STATES PATENT OFFICE.

BYRON G. DODGE, OF LANCASTER, AND THEOPHILUS WEAVER, OF HARRISBURG, PENNSYLVANIA; SAID WEAVER ASSIGNOR TO SAID DODGE.

AUTOMATIC CORK BLOCKING AND FINISHING MACHINE.

SPECIFICATION forming part of Letters Patent No. 374,891, dated December 13, 1887.

Application filed July 6, 1885. Serial No. 170,756. (Model.)

To all whom it may concern:

Be it known that we, BYRON G. DODGE and THEOPHILUS WEAVER, citizens of the United States, the first named residing at Lancaster, 5 county of Lancaster, and State of Pennsylvania, and the last residing at Harrisburg, in the county of Dauphin and the same State, have invented certain new and useful Improvements in an Automatic Cork Blocking and 10 Finishing Machine; and we do hereby declare that the following is a full, clear, and exact description of the invention, which will enable others skilled in the arts to which it appertains to make and use the same.

15 The object of our invention is to provide mechanism adapted to seize the bar of cork-wood when introduced thereto; to forward it to the knife for severing it into blunt wedge-form blanks, which have their heads and 20 per ends alternately reversed relative to the succeeding ones; to take hold of the blank before it is severed; to elevate the same as soon as severed; to rotate it and round and finish it by means of a knife adapted to gradually 25 come lower as to the plane of its rotation until the cork is finished, and mechanism for releasing the finished cork and again bringing the work-holding spindles to seize the next blank automatically, as hereinafter more fully 30 described, and pointed out in the claims, reference being had to the accompanying drawings, making a part of this specification, in which—

Figure 1 is a front elevation of our machine, 35 holding therein a cork as in course of being finished; Fig. 2, a top view of the same machine; Fig. 3, a perspective view of the support of the spindles; Fig. 4, a similar view of the spindle-shifting bar, with attachments and 40 its actuating-spring; Fig. 5, a similar view of the keeper-plate for said bar; Fig. 6, a similar view of the feed-slide and the feed-table; Fig. 7, a similar view of the swinging housing supporting the spindle-holding rack and the feed-table; Fig. 8, a similar view of a bar of cork-wood marked for blanks; Fig. 9, a cross-section of the rack-stem, its housing, the shifting-bar, its keeper-plate, and the attaching-stud of the housing; Fig. 10, a perspective view of 45 the adjustable top frame of the machine, provided with feed-motion attachments and with

the main transverseshift having cams thereon. Fig. 11 is a detail showing a cam and spur-gear.

In the further description similar reference- 55 letters denote the same parts in all the views.

The stationary machine-frame consists of the uprights 13 and the horizontal braces 2, 4, and 6. Upon the horizontal end braces 6 of said frame, which are at its mid-height, is supported the 60 adjustable frame A A' A'', which supports thereon all the coacting mechanisms excepting finishing-knife X and the means for rotating it and adjusting it vertically, its axis being in the shaft W³. Said shaft is supported 65 at its top in a bearing against the brace 2 by means of a cap-plate bolted thereto, and it has its foot end in a socket in the lever N², its sole support below. Said lever is pivoted to a part, N³, projecting from the brace 4, and the 70 opposite end, N⁴, of the lever is provided with the hanger or rod N⁴, whose hook-form upper end rests on the grooved periphery of the eccentric N' on the shaft W² vertically above said end N³. By these means said vertical 75 shaft W³ and the knife X thereon will be raised and lowered once during every revolution of the counter-shaft W², as required in rounding and finishing the work N in course of making each cork. Said work (shown as 80 a partially-finished cork in Fig. 1) is begun with a blank, a a', of blunt wedge form, as denoted by the lines on the bar of cork-wood shown in Fig. 8, in which the blunt point a and the head a' of each blank succeed, 85 respectively, the head and the blunt point of the next blank, that as little wood as possible shall be wasted. The blank which is foremost is seized by the work-holding spindles before it is severed from said bar, and held not only 90 while being severed, but until the work becomes a finished cork.

Our machine is therefore adapted to chuck or hold the work before it is severed from the bar, lift it from the feed-table, revolve it, 95 and when finished let it drop an instant before the spindles are lowered for seizing the next blank, as will be hereinafter more fully described.

Upon the horizontal braces 6 of the stationary frame is secured adjustably the movable frame A A' A'' by means of screw-bolts in-

serted into said braces through the slots A^5 in the transverse parts A^4 of said frame. The object of securing said frame adjustably is that as the knife X becomes of less diameter by being ground away the work-holding spindles Q Q' may be brought up to said knife by adjusting the frame forward on which said spindles are supported. Said frame consists of the parallel longitudinal front and rear braces, A A' , respectively, the front brace being widened vertically and joined to the rear one by the transverse parts A^4 , which are cut away at A^6 to clear the uprights 3 and permit the frame to be adjusted for the purpose described. Upon the transverse parts A^4 are the raised bearings a^3 , in which is journaled the counter-shaft W' , as shown. To the under side of the braces A A' is secured the main counter-shaft W' , as shown. Said counter-shafts communicate with each other by the bevel-gears W^6 and W^5 , respectively, and the shaft W' is provided with the pulley L^4 , whereby it connects by the belt q^2 with the counter-shaft Q^2 , which latter is provided with the pulley L^6 and with the pulleys r^2 , arranged as shown. The belts q^2 connect the last-named pulleys with the pulleys l^2 , respectively, on the shafts of the spindles Q Q' . The shaft W^2 is connected by any suitable means with the main driver-shaft W . To the front side of the widened part of the brace A' as a standard is connected, by the journal-stud b^2 , the housing B , formed with the undercut vertical way B^3 in its front for receiving and guiding therein the stem F of the vertically-movable rack F K k , which supports the spindles Q Q' in the rests K , as shown in Figs. 1 and 3. The journal-stud b^2 has its middle part, b' , formed as the journal on which the housing B swings or rocks, the latter being joined rigidly to the part b of said stud. The journal b' works in a bearing in the central part of the brace A , as shown. The inner end, b^2 , of said journal-stud is formed as a flat tenon, which snugly fits the longitudinal slot m in the spindle-shifting bar M^2 , which works back and forth thereon as its sole support, and said tenon also fits fixedly in a hole in the keeper-plate n , a transverse key, n' , retaining it securely therein. Said keeper-plate, being made cap form, embraces the upper and lower edges of said bar M^2 and sets or rides against the inner side of the brace A in such manner as to both keep said shifting-bar against the brace A and to guide it in its reciprocal movements.

The forward end, M^4 , of the shifting-bar M^2 is formed as an arc-head adapted to bear against the cam Z^2 on the shaft W^2 , whereby it is tripped or reciprocated at every revolution of the shaft. On the inner side of said arc-head M^4 is a receptacle in which is supported one end of the spiral spring N^2 . In the forward end of the keeper-plate n is the receptacle n^2 , in which is inserted the other end of said spring, which acts to keep said arc-head pressed against said cam, and therefore by its tension retracts said bar as soon as it has been fully

tripped. The rear end of said bar M^2 is formed with the part M^3 , to which is attached the lower end of the arm M , which is extended, as shown, to form connection with the shifting-spindle Q' , as follows: The upper end of said arm is a slotted or divided wrist, M' , adapted to embrace the shaft of the spindle Q' between the collars m^1 m^2 thereon, as shown in Fig. 2, 75 for retracting said spindle longitudinally when said shifting-bar is tripped by said cam. After the cam has its full throw the spindle is returned by spring-tension, as described, and the burrs upon the inner ends of the spindles Q Q' hold the work N between them during the greater part of each revolution of the shaft W^2 .

To the brace A is secured the post D , to be vertically adjustable, as by means of the screw-bolts D^2 , screwed into said brace inside through the slots D^3 in the post, thereby binding it against said brace. The top of the post has a V-shaped cut therein between the upwardly tapered abutments D' , and there extends into said cut the tongue E of the feed-table E , and it engages said abutments both ways for reversing the feed-table's position. The latter's throw is increased as said post is raised higher.

The means for actuating the feed-table are as follows: Said table is pivoted on top of the housing B to swing nearly horizontally when the housing swings vertically. The housing is provided with the journal-stud b^2 , rigidly attached thereto, which stud works in a bearing in the brace A , in which it is retained, as will be hereinafter explained, as well as the means for rocking the housing to have a uniform throw. Now the throw of the fulcral support of the feed-table being invariable, its own throw will be modified by the engagement of the tongue E' thereof with the abutments D' on said post, for the higher the post is set the less will be the lost motion at said tongue in its engagement with said parts of the post, and hence the greater will be the throw of the table both ways, and at the same time the greater will be the obliquity of the cut made by the knife X' in severing the blanks and by the knife X in finishing the work N . The said housing B and the spindle-holding rack F K k supported thereon are actuated as follows: The housing is provided with the arm B' , formed on its under side with a segmental bearing, against which the rotating cam S^5 works during about one-half of its revolution, 115 thus canting the housing one way. On the opposite side is the flat spring d , arranged to constantly bear against the housing for reversing its inclination after said cam has had its full throw. Said spring then firmly sustains 120 the housing's arm at rest on the cam while its circular part is engaging it.

The cam S^5 is formed on or secured to the disk of the spur-gear S^2 , and they unitedly are mounted on the journal-stud S^0 , by which they 130 are secured to the front face of the brace A , as shown. Upon the end of the main shaft W^2 , exterior to the front face of said brace, is keyed the spur-gear S' , having half the number of teeth

that the gear S^2 has, which is driven by it, thus causing the housing B and the rack F K k and the spindles Q Q' supported thereon to return to the same inclination only once for every 5 two revolutions of the shaft W^2 and for every two intermittent operations of the coacting mechanisms, as will be hereinafter described.

In front of the gear-wheel S^2 is the circular disk or guard S^3 , and in front of said disk is 10 the segmental cam S^4 , all said three parts being unitedly secured onto the shaft W^2 , the major part of the cam's periphery being circular and the less part thereof being an eccentric curve of greater radius. Upon said periphery 15 rests the foot J' of the lever J, which is pivoted at J^2 to the upright b^3 on the frame A A' A⁴, and has its opposite end formed with a longitudinal slot, through which a screw bolt or stud, f, connects the lever to the part 20 F of the rack F K k, as shown. Said slot is required to allow said stud to shift therein when the said housing swings back and forth. By said lever is said rack solely sustained, and 25 has its position determined by the position of the foot J' on the periphery of the cam S^4 . Said rack will therefore be raised and let down during every revolution of the cam, the major part of the cam's periphery allowing said foot and the rack supported thereby to stand stationary 30 in the elevated position during the major part of each revolution of the cam—that is, while the work N is being rounded and finished—the knife X being all the while gradually let down to the proper level for finishing 35 the work by the means already described. When the said rack, after finishing a cork, is let down by gravity, as the foot J' traverses the rest of the cam's periphery, the extended foot i of the trip-bar S lets down the circular 40 knife X', the bar being at top pivoted to the arm R, upon which the knife is journaled at its upper end. Meanwhile, as the said rack is being let down, the feed mechanism brings forward the cork-wood upon the table E, as 45 will be presently described. Upon the journal of the knife X' is fixed the pulley V', which is connected with the pulley T by the belt R'. The pulley T is double, and is connected by belt with a pulley, G', on the main shaft W 50 or other shaft. The pulley T is on a shaft which is the pintle of a hinge-joint at the union of the arm R with the swaying standard b⁴. The latter is pivoted below by the bolt C' to 55 an abutment of the frame A A' A⁴, and it is connected with the stem F of the rack by the link C³, pivoted to said stem, and having said hinge-pintle as its other pivot. The object of connecting said standard with the rack is that the knife X' shall be caused to descend 60 as nearly as possible onto the middle of the feed-table, longitudinally viewed, notwithstanding the reversing movement of the table.

The feed mechanism for working forward the bar of cork-wood upon the feed-table consists 65 of the slide or easing H³, retained and guided upon the feed-table, of the bent lever O, pivoted to the supports p² p³ at the pivots

p' p through the limbs O' O², as shown in Fig. 10, of the connecting-rod P, having its ends hooked onto or pivoted to said slide and lever at the eyes H² and t², respectively, of the disk L⁵, keyed on the shaft W² and provided with the tappet t, adapted to engage the foot O⁴ of said lever and to trip it at each revolution of said shaft for advancing said slide, and of the 70 spring Z, hitched at its ends to the frame A A' A⁴ and to the said foot O⁴, for retracting said slide after said tappet has passed said foot. Said slide is formed with two parallel sides, a bottom, and a cross-piece, H, at top, and said 75 sides have on them interiorly the ledges H⁴, arranged above the bottom far enough to admit snugly thereunder the feed-table E, as shown in Fig. 6. The flat springs H' h' are attached to said cross-piece and sides, as shown, 80 and they are adapted to bear on the bar of cork-wood to hold it properly on the feed-table and push it forward thereon, and the feed-table has thereon the flat spring H⁵, as shown, for retaining the said bar in place 85 while the slide is being retracted. The said slide operates with a definite throw in the forward direction, but returns by the sole energy of the spring Z.

Upon the feed-table at its inner end is the 90 stop e', adapted to arrest the advance of the bar of cork-wood on said table at or a little before the slide H³ has completed its throw. The springs H' h' hold onto said bar mainly by frictional contact, and will climb on the bar 100 to permit the slide to have its full throw. The throw of the slide may be changed by making the tappet t adjustable upon the disk L⁵, to stand farther off or nearer to the axis of the shaft W², for the throw of the slide will be as 105 is the radial distance of the tappet from said axis. The throw of the slide is completed an instant before the rotary severing-knife X' is caused to descend by the mechanism and as 110 described.

The main counter W² is provided with the bevel-gear W⁵, which meshes with the bevel-gear W⁶ on the shaft W⁴ and drives the same constantly. The latter shaft is coupled by the belt q² with the shaft Q and drives it intermittently, or only when the rack F K k is elevated, said belt being only then taut. By this arrangement the spindles Q Q' will not rotate when they are engaged in the act of seizing the blank before it is severed, but will rotate 120 as soon as said rack is raised.

We claim—

1. In a cork-cutting machine, the combination, with the stationary frame thereof, having the finishing-knife and its shaft supported theron, and means for raising and lowering said shaft, of the movable frame having transverse braces adapted to rest upon corresponding transverse parts of the stationary frame, and formed with slots therein running parallel with each other, of screw-bolts inserted through said slots into said transverse parts of the stationary frame for securing the movable frame adjustably thereon, of the work-hold-

ing spindles supported on the movable frame, and of means for operating the spindles, also mounted on and shifted with said frame when it is adjusted, substantially as and for the purposes set forth.

2. In a cork blocking and finishing machine, the combination, with the movable frame A A' A⁴, secured adjustably on the stationary frame thereof, of the swinging housing B, secured to the front brace, A, of said frame by the journal-stud b b², rigidly attached to the housing, of the feed-table E, pivoted upon the top of said swinging housing, of the post D, formed with the slots D³ in its basal end and secured therethrough by the bolts D² to the inner face of the brace A and having its upper end formed with the V-form cut between the projections D', the projecting tongue E' of the feed-table reaching into said cut and engaging said projections both ways for reversing said table's direction, of the pivoted cam S⁵, adapted to engage the under side of the arm B' of said housing for canting it, and of the spring d, arranged oppositely and exerted against the housing for returning it and holding it engaged with said cam, as and for the purposes set forth.

3. In a cork-cutting machine, the combination, with the stationary frame thereof and with the rounding and finishing knife mechanism mounted therein, of the movable frame A A' A⁴, having pivoted to its brace A the housing B, provided with the stud b b², to swing vertically upon the face of said brace, of the feed-table E, pivoted on the top of the extension C on the housing to swing horizontally and having the tongue E' projected beyond its pivot, of the vertically-adjustable post D, secured upon the inside of said brace and having said tongue working in the V-form cut in the top thereof for regulating the throw of said table, of the pivoted cam S⁵, coupled with the gear-wheel S², arranged for engaging the arm B' on said housing, of the spring d, arranged to bear against said housing and reciprocate with said cam for rocking the housing, and of the gear-wheel S' on the shaft W², engaged with the wheel on said cam for driving it and its coacting mechanisms, substantially as and for the purposes set forth.

4. In a cork blocking and finishing machine provided with the finishing-knife X and means for mounting and operating its shaft W³ to reciprocate vertically, the combination therewith of the pivoted housing B, formed with a vertical way thereon and with the lateral arm B', of the rack F K k, formed with the horizontal bearings K and having the stem F, fitted to and retained in said way to reciprocate vertically therein, of the work-holding spindles Q Q', supported axially in line with each other in said bearings, of the pivoted lever J, provided with the foot J' and having a slotted connection at its inner end with said rack, of the cam S⁴, supporting on its periphery said foot of the lever, and thereby said rack, of the cam S⁵, provided with the gear-wheel S², which

meshes with the gear-wheel S', so connected in action with said other cam that the latter shall revolve twice as fast as that having engagement with the arm B' for canting said housing, and of the spring d, co-operating with the cam S⁵ for working said housing both ways so that said knife shall equally finish corks whose points and heads are presented thereto alternately reversed, as herein set forth.

5. In a cork-cutting machine having the movable frame thereof provided with the vertically-swinging housing pivoted thereto, and having the horizontally-swinging feed-table E, pivoted on top of said housing, and working, by an extension thereof, in a V-form notch in the top of the post D, secured on said frame, the combination, with said parts, of the slide H³, guided on said table longitudinally and adapted by spring-detents H' h' to feed inward a bar of cork-wood on the table, of the rotary knife X', hung to swing vertically onto said table and sever a blank, a a', from said bar, so that each successive cut shall produce a blank head and point reversed to those of the preceding blank, of the lever O, coupled with said slide by the link P and having its foot O⁴ intermittently engaged by the tappet t and constantly retracted by the spring Z, for reciprocating said slide, of the intergeared cams S⁴ and S⁵, the former engaging the trip-bar S, for raising and lowering said knife, and the latter engaging the arm B' on said housing, and with the spring d, rocking the housing for changing the direction of said table, and of means for rotating said knife and cams, substantially as shown and described.

6. The combination of the feed-table E, pivoted on top of the housing B, which latter is pivoted to the front brace of the movable portion of the machine-frame to permit it to cant right and left, of the fixed parts D', between which a part of said table works for reversing the same when the housing cants either way, of the feed-slide H³, guided and reciprocated along the edges of said table and adapted for advancing the bar of cork-wood thereon, of the stop e², for arresting the advance of said bar, of means for changing the throw of said slide, of the rotary knife X', mounted and operated to swing on the hinging axis of the pulley T, by which latter it is rotated, and of the intergeared cams S⁴ S⁵ co-operating as set forth.

7. The combination, with the housing B, pivoted to the brace A to swing vertically, of the table E pivoted on top of said housing, and having an extension working in a notch in the top of the fixed post D, for reversing its direction, of the rack F K k, having its stem F guided in said housing, the lever J having a slotted connection with said stem and its opposite end pivoted to the upright b³, of the cam S⁴ supporting on its periphery the foot J' of said lever, that it and said rack shall be reciprocated at each revolution of said cam, of the arm R, pivoted to the swaying part b⁴ and provided with the trip-bar S, having its extended foot i also supported on the periphery of said cam, substantially as

described, so as to hold thereby said arm elevated an interval longer than said rack is elevated, to give the feed-motion time to act meanwhile, and of the rotary knife X', journaled on the free end of said arm and having its support b⁴ joined to said stem by the link c³, as set forth.

8. In a cork blocking and finishing machine, the combination, with the feed-table E, pivoted to and adapted to be reversed alternately by the engagement of an extension thereof with a fixed post, as set forth, of the feed-slide H³, provided with the inner ledges, H⁴, for guiding it upon said table, which is inserted between its bottom and said ledges, and also provided with the flat springs H' h', adapted to bear on and engage the bar of cork-wood, of the spring H⁵ on said table, adapted to engage the under side of said bar, and of the rod P, pivoted to said slide and to the pivoted rocking lever O, by which the slide is reciprocated and said bar fed up, substantially as and for the purpose set forth.

9. In a cork-cutting machine, the combination of the feed-table E, pivoted to a movable support on the machine-frame, of the slide H³, provided interiorly with the guiding-ledges H⁴, whereby it is guided and retained on said table, as shown, and also provided with the springs H' h', adapted to bear on and push forward a bar of cork-wood on said table when said slide is advanced, the spring H⁵ on the feed-table, adapted to retain the bar of cork-wood in place thereon when the slide is being retracted, of the lever O, pivoted to supports on parts of the machine-frame and having the foot O⁴ extended below the axis of said pivotal points and rebent, as shown, of the rod P, having its ends joined by pivotal connections with said slide and lever, of the shaft W², provided with the disk L⁵, armed with the tappet t, adapted to have intermittent connection with said foot, and of the spring Z, attached to said lever and exerted to retract it and said slide, substantially as set forth.

45 10. In a cork blocking and finishing machine, the combination, with the movable portion of the machine-frame, of the vertically-swinging housing B, provided with the stud b b², whereby it is pivoted to the front brace, A, of said portion, the housing being formed with the vertical way B³ in it, of the rack F K k, formed with the supports K, having journaled therein the spindles Q Q', axially in line with each other, and with the stem F guided in said way, 55 of the longitudinally-shifting bar M², formed with the slot m therein, in which it reciprocates upon the flat part b² of said stud, whereby the bar partakes of the swinging movement of the housing, said bar having one of its ends formed as an arc-head, m³, adapted as an extended vertical bearing against which the eccentric or cam Z² works for reciprocating the bar, and having its opposite end provided with the coupling-arm M, formed with the divided wrist M' above, whereby it embraces the shaft of the spindle Q', provided with the collars m' m², as shown, of the keeper-

plate n, formed with recessed base to admit and permit to be shifted therein said bar, the plate being secured upon the end b² of said stud and formed with the receptacle n² in its end, and of the spring N³, having its ends set in the receptacles M⁴ and N⁴, and exerted to retract said bar and thereby bring the spindle Q' to bear against the work N, substantially as shown and described.

11. In a cork blocking and finishing machine, in combination with the stationary frame thereof, provided with the knife X, having its shaft W³ vertically carried on the pivoted lever N² and thereby supported, of the rod N⁴, attached to the free end of said lever and hooked onto the grooved eccentric N', of the work-holding spindles Q Q', supported axially in line with each other in bearings in the parts K of the rack F K k, of the housing B, pivoted to the movable frame A A' A⁴ and having the stem F of the said rack supported in a vertical way therein, of the pivoted lever J, having a slotted connection with said rack and provided with the foot J', arranged to constantly rest on the periphery of the cam S⁴ for thereby sustaining said rack, of the counter-shaft Q², journaled in the extensions k of said rack and coupled by the belts q with the shafts 95 of said spindles, of the counter-shaft W', journaled upon the transverse braces of the frame A A' A⁴, and coupled with said shaft Q² by the belt g², in manner set forth, that said spindles shall be run only when said rack is elevated, of the shifting-bar M², provided with the arm M and thereby coupled with the shaft of the spindle Q', and of a cam on the shaft W², adapted to engage said shifting-bar by an endwise thrust at each revolution of the cam 105 for retracting thereby said spindle Q' after the finishing-knife has performed its function, substantially as set forth.

12. The cork blocking and finishing machine-frame provided with the rotary knife X, having its shaft W³ supported to have a vertical movement, in combination with the rotary severing-knife X', having its shaft journaled in the free end of the vertically-swinging arm R, of the belt R', coupling the shaft of said knife X' with the pulley T, mounted loosely upon the hinge-pintle which connects said swinging arm to its swaying standard b⁴, of the belt R', coupling said pulley with a driver-pulley, of the trip-bar S, pivoted to said arm 120 and having its extended foot l supported on the periphery of the cam S⁴, said bar having a slotted connection with the lever J, whereby it is guided in its vertical movements, of the strap c³, pivoted to said standard b⁴ and at its 125 opposite end to the housing B, so that as the latter cant said standard shall be caused thereby to accompany it, or to sway, and thus bring the severing-knife properly in place upon the cork-wood on the feed-table E, of the lever J, pivoted to the fixed standard b³ and having a slotted connection at its opposite end with the rack F K k, and being provided with the foot J', whereby it is supported on the periphery 130

of the cam S^4 , by which said lever and rack are vertically reciprocated at each revolution of the cam for bringing the work gradually up to be rounded and finished by the knife X , of 5 the shifting-bar M^2 , provided with the arm M , whereby it is connected with the shaft of the spindle Q' , as set forth, and also provided with the arc-head M^1 , and of the spiral spring N^3 , having its one end inserted in a receptacle 10 next said head and its other end inserted in a receptacle, n^2 , on the adjacent end of the keeper-plate n , the spring being exerted to

hold said arc-head in contact with the cam Z^2 on the shaft W^2 , whereby it is moved at each revolution of said shaft, and by these means 15 retracting the spindle Q' for releasing the finished work, all the co-operating mechanisms performing their functions substantially as and for the purposes set forth.
